DISPLAY RACKS

Abram Levy, Jr., Atlanta, Ga.

Application January 2, 1952, Serial No. 264,484

2 Claims. (Cl. 211—45)

1

This invention relates to an article display rack.

An object of this invention is to provide an article display rack for displaying articles such as swatches or pieces of fabric.

Another object of this invention is to provide a display rack of this kind which includes means for removably mounting the articles in the rack so that any selected one or more of the articles may be removed or replaced.

A further object of this invention is to provide a collapsible display rack with an improved case or covering for holding the rack in collapsed carrying position.

With the above and other objects in view, my invention consists in the arrangement, combination and details of construction disclosed in the drawings and specification, and then more particularly pointed out in the appended claims.

In the drawings:

Figure 1 is a detailed side elevation of a collapsible display rack constructed according to an embodiment of this invention showing the rack in a flexible carrying case.

Figure 2 is a detailed end elevation of the rack in extended position.

Figure 3 is a fragmentary front elevation partly broken away and in section.

Figure 4 is a fragmentary sectional view taken on the line 4—4 of Figure 3.

Figure 5-A is a fragmentary sectional view taken on the line 5-A-5-A of Figure 3.

Figure 6 is a fragmentary vertical section similar to Figure 4 showing the locking means for the articles in released position.

Figure 7 is a fragmentary sectional view taken on the line 7--7 of Figure 4.

Figure 8 is a fragmentary front elevation showing the manner in which the articles are removed from or replaced on the rack.

Figure 9 is a fragmentary sectional view taken on the line 9--9 of Figure 2.

Figure 10 is a fragmentary sectional view taken on the line 10—10 of Figure 2.

Figure 11 is a plan view partly broken away of one of the article supporting rods.

Referring to the drawings, the numerals 15 and 16 designate generally a pair of inverted U-shaped frame members which are hingedly connected together at their upper ends as indicated at 17. The frame members 15 and 16 are of similar construction and each frame member is formed of a pair of parallel legs 18 connected

5 connected together at their upper ends by a connecting member or bight 19. The frame members 15 and 16 are of tubular construction and, as herein shown, are substantially squared in transverse section;

The lower ends of legs or vertical frame members 18 have cushion feet 20 mounted thereon. A flexible webbing 21 is secured between the legs or sides 18 being mounted on upper and lower rods 22 and 23, which are fixed between the sides 18. The webbing 21 provides a means in the form of a flexible backing against which the articles, which in the present instance are swatches, may rest when the rack is in its open or extended display position. The inner sides or walls 24 of each side member 18 are formed with an elongated slot 25 extending from a point above the webbing 21 to the upper portions of the side members 18.

20 A plurality of article-supporting rods 26 are slidably and removably mounted within the slots 25. Each rod 26 is formed after the manner shown in Figure 11 and includes an elongated straight rod member 27 formed with a right angular locking member 28 at one end and with a second right angular locking member 29 at the opposite end. The rod 27 is formed with an offset 30 disposed substantially midway between the ends of the rod, and rod 26 is also formed 30 with a second offset 31 which constitutes a keeper, the purpose for which will be hereinafter described.

One or more swatches or other articles 32 are adapted to be mounted on each rod member 26 and the articles 32 are adapted, when the rack is in its open extended position, to overlap each other. In order to provide a means whereby the rods 26 will be releasably locked between the sides 18, I have provided a locking bar 33 which is pivotally mounted on a pivot bolt 34 disposed below the lower end of one of the slots 25. The locking member 33 is formed of a flat bar or link having an edge thereof confronting the concave side of the keeper or offset 31, and when locking bar 33 is in its locking position, the adjacent or outer edge of bar 33 will be disposed within the concave cavity of the keeper 31. The locking member 33 is releasably held in a locked or released position by a releasing bar 35 which is pivotally mounted on a pivot 36.

A U-shaped locking member 37 is fixed to the bar 35 projecting below the lower end thereof, and a pin 38, which extends between the parallel sides of the locking member 37, engages

in an elongated slot 39 formed in the upper end of locking bar 33. A right angularly disposed handle 40 projects from the locking member 37 and provides a means whereby the locking member 37 with the locking bar 35 may be moved to either a released or a locked position. As shown in Figure 6, the locking bar 35 is also formed with an elongated slot 41 through which the pivot member 36 loosely engages so that the two fixedly connected together locking members 35 and 37 may be manually moved upwardly to a released position.

A spring 42 is connected between the locking member 35 and the pivot bolt 36 and provides a means whereby the locking members 35 and 37 will be constantly urged downwardly to a locked position. When the locking members 35 and 37 are in a locked position which is substantially in alignment with the adjacent side member 18 and with the locking bar 33, the inner edge of locking bar 33 will be disposed in contacting relation with the bight of the U-shaped locking member 37. A U-shaped bail or handle 43 is secured to one of the sides 18 between the ends thereof and the bail 43, which has a leather or flexible covering 44 disposed thereabout, is secured to a side 18, as shown in Figures 9 and 10, by extending the bail 43 through aligned openings 45 formed in the side 18 and then bending the free end of the bail in substantially U-shape so that the free end of the bail will overlie the outer side of the side member 18. This free end designated 46 is secured to the side 18 by means of a fastening member 47. The two frame members 15 and 16 are adapted to be held in upwardly convergent relation, or in a display position, by means of pairs of pivotally connected together links 48 and 49 which are of conventional construction.

When the rack structure is in a collapsed position with the frame members 15 and 16 disposed in substantially parallel position, the rack structure is adapted to be incased in a flexible covering 50 which, as shown in Figure 1, is open at one end so that the sides or legs 18 may partially project from the casing. The casing 50 is formed with an opening on one lengthwise edge thereof through which the bails or handles may project so that the rack may be conveniently carried.

In the use and operation of this rack structure, when it is desired to display articles carried by either one of the frame members 15 or 16, the rack is set up with the frame members 15 and 16 in upwardly convergent relation, as shown in Figures 2 and 4. The articles such as swatches or the like may be selectively displayed and when a lower article is to be displayed, the upper articles may be swung over the top of the rack structure by drawing the articles and the supporting bars or rods 26 upwardly to the position shown in Figures 2 and 3. The articles may then be draped over the top of the rack structure.

If it is desired to remove any one or more of the articles, the locking bar 33 is moved to an inner released position by pulling the handle 40 upwardly and at the same time swinging the locking members 35 and 37 inwardly to the position shown

in Figure 6. The selected one or more of the rods 26 may then be removed from the rack by turning the rod so as to dispose the locking lugs 28 and 29 in substantial alignment with the slots 25. At this time one end of the rod 26 may be raised upwardly until such end is moved out of the slot 25.

The rack structure herein disclosed will provide a convenient, compact and light-weight display means for articles such as swatches or flexible samples which will be maintained in a neat condition and will not become wrinkled or the like when the rack structure is in a collapsed carrying position. While I have shown the frame members 15 and 16 as being formed out of polygonal tubular material such as aluminum or the like, it will be understood that these frame members may be formed out of tubular material of any desired cross-sectional configuration.

What is claimed is:

1. A display rack comprising a pair of inverted U-shaped frame members, hinge means pivotally connecting the bights of said members together, a webbing secured between the sides of each member, said sides having confronting longitudinal slots extending above said webbing, a plurality of article supporting bars extending between said sides and engaging in said slots, each bar having a right angular projection at each end thereof, an offset keeper carried by each bar adjacent one end thereof, a locking bar pivotally secured at one end to one of said sides and adapted to engage in a keeper when said locking bar is in locked position, and spring-pressed latching means for holding said locking bar in locked position.

2. A display rack comprising a pair of inverted U-shaped frame members, hinge means pivotally connecting the bights of said members together, a webbing secured between the sides of each member, said sides having confronting longitudinal slots extending above said webbing, a plurality of article supporting bars extending between said sides and engaging in said slots, each bar having a right angular projection at each end thereof, an offset keeper carried by each bar adjacent one end thereof, an offset member disposed medially between the ends of each supporting bar providing means for manually turning each bar to dispose the projections in registry with said slots, a locking bar pivotally secured at one end to one of said sides and adapted to engage in a keeper when said locking bar is in locked position, and spring-pressed latching means for holding said locking bar in locked position.

ABRAM LEVY, JR.
